UNITED STATES PATENT OFFICE.

THOMAS C. CHRISTIE AND ELMER A. EDMON, OF LEBANON, OHIO.

ENGINE-STARTER.

1,253,150.

Specification of Letters Patent. Patented Jan. 8, 1918.

Application filed October 23, 1915. Serial No. 57,600.

To all whom it may concern:

Be it known that we, THOMAS C. CHRISTIE and ELMER A. EDMON, citizens of the United States, residing at Lebanon, in the county of Warren and State of Ohio, have invented new and useful Improvements in Engine-Starters, of which the following is a specification.

This invention relates to engine starters of the mechanical type the object in view being to provide a starter applicable to the engines of automobiles and similar vehicles, the starting mechanism being controlled by the driver of the machine while in his seat and being of such a nature that it is impossible for the operator to be injured by the starter in the event of the engine back firing or starting to turn in the wrong direction.

20 A further object of the invention is to provide novel means whereby the starting arm which turns the engine shaft is automatically tripped at both limits of its movement so as to disengage the starting mechanism from the engine shaft.

25 One of the principal features of this invention resides in the particular construction of the starting arm whereby increased throw and leverage is obtained for effecting a correspondingly increased throw or turning movement of the engine shaft.

30 With the above and other objects in view, the invention consists in the novel construction, combination and arrangement of parts, as herein described, illustrated and claimed.

In the accompanying drawings:

35 Figure 1 is a front elevation partly in section showing the starter of this invention applied to the engine of an automobile.

40 Fig. 2 is a plan view thereof partly in section also shown applied.

Fig. 3 is a vertical longitudinal section showing the operating means.

45 Fig. 4 is an enlarged front elevation showing the operating arm and its extension in their initial positions.

Fig. 5 is a similar view showing the final position of said parts.

50 Fig. 6 is a fragmentary rear elevation of a portion of the main starting arm, the dog and spring.

Fig. 7 is a detail perspective view of the pivoted arm extension.

Fig. 8 is a fragmentary section similar to Fig. 4 but looking toward the opposite side 55 of the main starting arm.

Referring to the drawings, 1 designates a ratchet wheel which when in its working position has a fixed relation to the crank shaft of the engine designated generally at 60 A. In the preferred embodiment of this invention the ratchet wheel 1 is carried by or formed integrally with a belt pulley 2 which is substituted for the belt pulley now usually fastened on the crank shaft of the engine 65 and around which the belt passes for driving the fan used in maintaining the engine in a cool condition, said fan being arranged between the front end of the engine and the radiator. Extending forwardly from the 70 ratchet wheel 1 is a stub shaft 3 on which is fastened the clutch member 4 which is adapted to be engaged by a coöperating clutch member on the inner end of the shaft of the crank by means of which the engine is 75 ordinarily started.

5 designates a collar which loosely encircles the clutch member 4 and is provided with an outwardly extending main starting arm 6 having pivotally connected to the extremity thereof at 7 an extension arm 8 preferably composed of two side members which straddle the extremity of the main arm 6 and which have journaled between the outer extremities thereof a chain pulley 9 the 80 purpose of which will presently appear. A stop in the form of a pin 8' on the extension arm 8 contacts with the main arm 6 and serves to limit the pivotal movement of said extension arm in an inward direction 90 so that an effective leverage or pull on the arm 6 is insured.

A dog 10 is pivotally mounted at 11 on the main arm 6 and is provided with a projecting tooth 12 to coöperate with the teeth 95 of the ratchet wheel 1 for the purpose of turning said ratchet wheel in a direction which will turn the crank shaft of the engine to start the latter. The dog 10 is provided with two tripping faces 13 and 14 100 which extend or project beyond the opposite sides or edges of the arm 6 so as to come in contact with fixed stop surfaces 15 which are shown as formed by the side portions of the pan 16 which extends under the engine. 105 In the working stroke of the arm 6, the trip-

ping face 13 comes in contact with the pan when the arm reaches the limit of its movement in that direction. In the return movement of the arm 6, the tripping face 14 of the dog operates to throw the latter out of engagement with the ratchet wheel. The dog 10 is pressed toward the ratchet wheel 1 by means of a backing spring 17 so that the dog is forced into engagement with the ratchet wheel as soon as the arm 6 starts on its working stroke.

The tripping faces of the dog are disposed at such angles that the dog is released by substantially vertical pressure against the fixed stop surfaces at both ends of the throw of the main starting arm, the dog being formed with a locking notch 13' in one of its tripping faces to receive one of said stop surfaces and prevent further pivotal movement of the dog when the main arm has reached the full limit of its working stroke, the dog serving to limit said working stroke of the main starting arm.

The mechanism hereinabove described is manually operated by means of a handle 18 arranged in rear of the dash 19, said handle being fastened to the rear extremity of a pull rod 20 the latter passing through the dash board and being normally held in its initial position by means of a cushioning spring 21 which is interposed between a plate 22 on the dash and a shoulder 23 on the pull rod. Connected to an eye 24 at the forward end of the push rod 20 is a chain 25 which passes around a guide pulley 26 journaled in a bracket 27 fastened to the frame of an automobile at one side of the engine as shown. The chain 25 then passes around the pulley 9 of the extension arm and then back to the bracket 27 to which it is fastened at 28.

In order to provide for the quick return movement of the starting arm 6, I employ a coiled contractile spring 29 one end of which is secured at 30 to the frame. To the other extremity of said spring is fastened one end of a short chain 31, the opposite end of said chain being fastened to a grooved pulley face 32 on the collar 5 above described. In operation, the driver grasps the handle 18 and pulls the same rearwardly causing the chain to swing the main arm 6 and the extension arm 8 in a direction which will cause the dog 10 to engage the ratchet wheel 1 and impart a partial turning movement in the proper direction to the crank shaft of the engine. As soon as the handle 18 is released, the spring 29 restores the starting arm to its initial position. This operation 60 may be repeated as frequently as necessary in order to start the engine. At both limits of movement of the starting arm the dog 10 is tripped out of engagement with the ratchet wheel 1 thus preventing injury to 65 the hand and arm of the operator as well as

the starting mechanism of this invention. Should the engine kick backwardly before the arm 6 has reached the limit of its working stroke, the only result will be to snatch the handle 18 out of the operator's hand and just as soon as the arm reaches its initial position the dog will be automatically tripped thus preventing injury to the starting mechanism.

Equipping an automobile engine with the starting mechanism hereinabove described will not interfere with the free use of the ordinary hand starting crank, so that both means of starting the engine may be employed as may be found necessary or advisable under existing conditions.

Having thus described our invention, we claim:

1. The combination with the crank shaft of an engine, of a ratchet wheel having a fixed relation to said shaft, a normally loose collar on said shaft at one side of the ratchet wheel, a main starting arm extending from said collar and having a fixed relation thereto, a dog having a pivotal mounting on and carried by said arm and having two tripping faces projecting laterally on opposite sides of said arm, means for causing said dog to engage the ratchet wheel as soon as the arm is moved from its initial position, fixed stop surfaces with which said tripping faces contact at the limits of movement of said arm, an extension arm pivotally attached to the main starting arm and having a pulley at its free end, means for retracting the starting arm, a manually operable pull chain controlled from the driver's seat and passing freely around said pulley and having one extremity thereof attached to a fixed point, and a stop on said extension arm adapted to contact with the main starting arm to limit the inward movement of the extension arm at the initial end of the throw of said main starting arm.

2. The combination with the crank shaft of an engine, of a ratchet wheel having a fixed relation to said shaft, a collar having a normally loose relation to said shaft and ratchet wheel, a main starting arm extending from said collar and fixed in relation to the latter, a dog having a pivotal mounting on and carried by said arm and having front and rear tripping faces projecting beyond opposite faces of said arm, means for causing said dog to engage the ratchet wheel as soon as the arm is moved from its initial position, fixed stop surfaces with which said tripping faces contact at the limits of movement of the dog, an extension arm pivotally attached to the main starting arm, a manually operable pull chain controlled from the driver's seat for imparting a working stroke to said starting arm, and means for retracting said starting arm, said tripping faces of the dog being dis-

posed at such angles that the dog is released by substantially vertical pressure against the fixed stop surfaces at both ends of the throw of the main starting arm, the dog being formed with a locking notch 13' in one of its tripping faces to receive one of said stop surfaces and prevent further pivotal movement of the dog when the main arm has reached the full limit of its work-

ing stroke, the dog serving to limit said working stroke of the main starting arm.

In testimony whereof we affix our signatures in presence of two witnesses.
